UNITED STATES PATENT OFFICE.

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK.

RAIL JOINT.

Application filed June 3, 1922. Serial No. 565,549.

To all whom it may concern:

Be it known that I, CLARKSON A. DISBROW, a citizen of the United States, residing at New Rochelle, in the county of Westchester and State of New York, have invented certain new and useful Improvements in Rail Joints, of which the following is a specification.

This invention relates to an improvement 10 in rail joints, and has for its primary object a novel construction providing increased flexibility in the joint bar, enabling it better to accommodate itself to the wave motion in the rail and easing the central portion 15 of the joint bars from bending and shearing strains.

In the usual type of joint bar, which is of 20 the same vertical height as that of the fishing spaces of the rails, the joint bars fit the rails throughout the entire length of the joint. In such a construction the bending and shearing strains are localized or 25 concentrated at the center of the bar. That is due to the fact that as the wave motion 25 of the rail approaches the joint, the rail is kept from yielding because of the joint bar, and the joint bar is held from yielding by the rail until the center of the joint is reached.

Consequently, in the usual rail joint in 30 which the joint bar fits the rail joint fishing for the entire length, practically all of the bending due to approaching wheel loads takes place at the center of the bar where 35 the rail is in two parts and where the joint bar has to withstand the shearing strains also. To relieve that condition to a material extent it is the purpose of the present invention to provide a construction wherein 40 the joint bar is tightly fitted to a bearing at the center and ends of the joints leaving the intermediate portions of the bar free of contact with the rail, thus contributing materially to the flexibility of the bar between 45 the center of the joint and the ends of the rails and, consequently, leaving the center portion of the joint bar practically free from bending strains and required only to withstand the shearing strains.

Furthermore, in the improved construction according to the present invention, the bending strains are not only removed from the center of the joint to a very material extent, but the bar distributes the bending strains more or less throughout the length

of the bar, thus increasing its stability, at the same time not interfering at all with the splicing function thereof to securely and properly fasten together the two rails.

A further practical and useful object of 60 the invention is to provide a construction, whereby the joint will give a proper and full support to the rail ends. It is well-known that in the usual type of joint bar, which contacts with the rail throughout 65 the fishing, there might be a lack of support at the rail ends because of the variation in the rolled joint bar and in the rails themselves. Such a condition causes wear to start quickly, and, should the joint bar entirely fill the fishing space of the rails snugly a short distance either side of the center, that would have the effect of preventing the center of the bar from being adequately drawn into the rails to give proper support. 70 As distinguished from such conditions which are considered defects in the ordinary rail joint, the present invention provides a construction wherein the joint bar at both sides of the center of the joint is out of contact 75 with both the head and base flange of the rail. This form of construction allows the center part of the bar to be tightly and snugly drawn in by the bolts, thereby giving full and proper support to the rail ends. 85

Another object of the invention is to provide a construction of rail joint wherein relatively hard metal-bearing plates are utilized as the bearing surfaces of the rail joint, the said bearing surfaces being spaced 90 apart and thus relieving the joint of the excessive binding fit between the joint bar and the rails, which in the ordinary construction frequently interferes with the free movement of the rails under temperature 95 conditions.

Another object of the invention is to provide a form of construction wherein the same rolled section constituting the joint bar proper is available for rails having 100 fishing spaces of different dimensions.

With these and other objects in view which will more readily appear to those familiar with the art, as the details of the invention are better understood, the same 105 consists in the novel construction, combination and arrangement of parts hereinafter more fully described, illustrated and claimed.

The essential and fundamental features 110

of the invention are necessarily susceptible of embodiment in different forms of construction, but certain preferred and practical forms are shown in the accompanying drawings in which—

Figure 1 is a perspective view of the simple form of rail joint embodying the improved features contemplated by the present invention.

10 Figure 2 is a detail perspective of one of the bearing shim units shown at the ends of the joint in Figure 1.

Figure 3 is a detail perspective of a center bearing shim unit which may be employed in Figure 1.

15 Figure 4 is a perspective view of a joint showing a modification wherein the bearing shim units have their upper and lower bearing flanges respectively of different widths 20 to provide varying areas of different extent.

Figure 5 is a detail perspective of one of the modified forms of bearing shim units included in the joint of Figure 4.

25 Figure 6 is a perspective view of a joint showing a further modification of the invention wherein is employed a bearing shim unit co-extensive with the length of the joint and having bearing flanges at intervals thereon.

30 Figure 7 is a perspective view of the continuous type of bearing shim unit shown in Figure 6.

Figure 8 is a detail view similar to Figure 6 showing a rail of a different fishing height 35 to illustrate the feature of using the same joint bar with rails of different fishing height by varying the thickness of the bearing plate or shim.

Like references designate corresponding 40 parts throughout the several figures of the drawings.

The distinctive feature of the present invention, as pointed out, is the provision of bearings for the joint bar so disposed and 45 arranged as to permit the bar to be snugly drawn in to a tight fit at the center of the joint and at the ends of the joint, leaving the intermediate portion of the bar out of contact and therefore entirely free from the 50 head, web and base of the rail, thus relieving the center of the joint from bending strains and distributing the latter more or less uniformly throughout the length of the bar. At the same time these bearings for 55 the bar, preferably being of harder metal than the bar and the rail, admit of more ready movement of the rails in the joint when influenced to expand or contract under temperature conditions.

60 In carrying out these particular objects and features of the invention, primarily there is employed a joint bar designated by the numeral 1 which may be of any desired type though preferably a rolled bar of a

uniform section throughout and with less 65 fishing height than the fishing dimensions of the rail R. That is to say, the joint bar 1 is of less height vertically than the fishing distance between the underside of the rail head and the upper side of the rail flange, 70 and to provide for fitting the bar to the rails a plurality of bearing shim units, designated in Figure 1 A, B and C respectively, are combined with the joint bar.

In the embodiment shown in that figure 75 of the drawings, the shim unit A is arranged at the center of the joint and is interposed between the central part of the joint bar and the two rail ends within the joint, while the shim units B and C are respectively located 80 at opposite ends of the joints, being interposed between the ends of the joint bar and the rails. The result of this spaced arrangement of the shim units A, B and C is to leave the intermediate parts I of the joint 85 bar free, that is the parts of the bar between the central shim unit A and the end shim units B and C are entirely out of contact with the head, web and flange of the rails. Therefore, the said intermediate non-contacting portions I of the splice bar are free to flex between the bearing shim units A, B and C, thereby better adapting the bar to the passing of the rail wave motion through the joint; consequently, relieving the joint from concentrated bending strains at the center and requiring the central part of the joint practically to withstand only the shearing strains.

The bearing shim units may be in different forms of construction and may be made of different kinds of metal. It is preferable, however, that the shim units be made of harder steel than the joint bar and the rail so that the "freezing" together of tightly 100 contacted metal surfaces, such as frequently occurs in the ordinary rail joint, is obviated and the rails will have greater freedom to contract and expand under temperature conditions. Also it is desirable, as well as 105 preferable, in carrying forward the invention to have the shim units in vertical alignment with the joint or clamping bolts so that they may be snugly held in place by the tightening of the bolts and so that firm and 110 rigid bearing supports may be provided for the rails at the spaced points, usually at the center of the joint and at the ends as shown in Figure 1 of the drawings.

The desirable general form of the shim 115 units is illustrated in Figure 2 of the drawings, wherein there is shown a unit consisting of a web or body member 2 provided with the upper and lower outstanding bearing flanges 3 and 4 respectively fitting between the upper surfaces of the joint bar and the underside of the rail head, and between the lower surface of the joint bar and

the upper side of the rail flange. This form of construction is in effect a channel receiving therein the joint bar, and the clamping bolt, passing through the joint bar and a bolt 5 hole 4^a in the shim unit, provides for snugly holding the bar within the shim unit and in turn holding the latter in firm bearing contact with the rail surfaces. It will thus be seen that the clamping bolts are preferably 10 utilized to hold the shim units in their proper position and, where bolt locations will not permit of extending the bolts directly through the bolt holes in the shim unit, the shim unit may be provided at its edges with 15 bolt-engaging notches 5, such as shown in the shim plate unit A of Figures 1 and 3 of the drawings.

To illustrate the range of modification that may be resorted to in the construction 20 of the shim units, there is shown in Figures 4 and 5 of the drawings a shim unit wherein the upper bearing flange 3 thereof is narrower and of less bearing surface area than the lower and wider bearing flange 4. This 25 form of construction is desirable for the purpose of giving more bearing surface over the rail flange, so that the loads are distributed over a greater area of the rail flange. This is advantageous because of the 30 rail flange being thinner than the rail head.

Another embodiment of the invention, including other features, is shown in Figures 35 6 and 7 of the drawings. These figures are 7 illustrative of the application of the bearing shim unit feature to a longer rail joint, such as a six-bolt joint, wherein more than three bearings between the joint bar and the rail might be desirable; and also wherein these 40 bearings might be graduated in area, that is of greater extent or area at or adjacent the meeting ends of the rail and diminishing in extent or area toward the ends of the joint. Also, as shown by this form of the invention the various bearings of whatever 45 extent or arrangement may be carried by a single full length bearing shim unit, designated by the letter E. This bearing shim unit may consist of a web or body plate 6 which extends the full length of the joint 50 and is formed at its top and bottom edges respectively with upper and lower bearing flanges 7 and 8 respectively, which are paired together, at the bolt locations to carry out that feature of the invention which resides 55 in having the bearing flanges or bearing members in or substantially in the vertical plane of the clamping or joint bolts so that the rail joint may be securely tightened in these locations.

60 Also another phase of the invention is shown in Figure 8 of the drawings which represents a rail having a fishing space of different dimensions from the dimensions of the fishing space of the rail shown in Figure 65 6, and at the same time admitting of the

use of the same rolled section of joint bar. In such a case it is only necessary to vary the thickness of the bearing flanges or bearing members of the shim units, the difference in the fishing height of the two rails being 70 compensated for by the difference in thickness of the bearing flanges or bearing members.

In the embodiment of the invention herein shown and described, the bearing shim 75 units are shown of a form and construction which admits of the same being securely fastened in place in bearing contact with the rail without possibility of displacement or creeping, due to the joint or clamping 80 bolts being utilized as the fastening means. But it should be understood to be within the purview of the invention to secure these bearing members or plates in their proper locations by any suitable means such for instance as by welding to the joint bar.

From the foregoing it is thought that the construction and many advantages of the herein described improvements will be readily apparent without further description, 90 and it will also be understood that various changes in the form, proportion and minor details of construction may be resorted to without departing from the spirit or sacrificing any of the advantages of the in- 95 vention.

I claim:

1. A rail joint including the rails, a joint bar of less fishing height than that of the rails, and bearing shim units interposed between the bar and the rails at the central and end portions of the joint.

2. A rail joint including the rails, a joint bar of less fishing height than that of the rails, and hard metal bearing shim units 105 interposed between the bar and the rails at the central and end portions of the joint.

3. A rail joint including the rails, a joint bar spaced from the head and flange of the rail, and bearing shim units interposed 110 between the bar and the rail at the central and end portions of the joint.

4. A rail joint including the rails, a joint bar of less fishing height than that of the rails, and a plurality of spaced bearing shim 115 units interposed, at intervals, between the joint bar and the fishing surfaces of the rail leaving the intervening parts of the bar free to flex with the rail wave motion.

5. A rail joint including the rails, a joint bar of less fishing height than that of the rails and a plurality of bearing shim units 120 interposed at intervals, between the bars and the rails, each of said units consisting of a web or body portion and upper and lower 125 bearing flanges.

6. A rail joint including the rails, a joint bar, the joint bolts and a plurality of spaced bearing shim units, arranged at joint bolt 130 locations and having their bearing portions

- interposed respectively between the bar and the head and flange of the rails.
7. A rail joint including the rails, a joint bar of less fishing height than that of the rails, and hard metal bearing members interposed respectively between the bar and the head and flange of the rail, the said bearing members being arranged at spaced apart intervals and each pair of such members disposed in the vertical plane of a clamped bolt or bolts.
8. A rail joint including the rails, a joint bar, a plurality of connected upper and lower bearing plates arranged at spaced intervals in the joint and disposed in fishing position between the joint bar and the rails, and means for retaining said plates against movement longitudinally of the joint bar.
9. A rail joint including the rails, a joint bar, and bearing surfaces for the bar formed of hard metal, the said surfaces being spaced to distribute the bending strains on the bar on opposite sides of the center thereof.
10. A rail joint including the rails, a joint bar, and a plurality of spaced bearing shims

interposed between the joint bar and the rails respectively at the ends and central part of the joint, the centrally located shims bridging the rail ends, and means for preventing longitudinal displacement of the spaced shim units.

11. A rail joint including the rails, a joint bar, and a bearing shim unit interposed between the bar and the rail, said unit having upper and lower flanges respectively having different bearing areas.

12. A rail joint including the rails, a joint bar, and a bearing shim unit interposed between the bar and the rail, said unit consisting of a web or body portion having upper and lower bearing flanges, the upper of said flanges being narrower and having less bearing area than the lower of said bearing flanges.

In testimony whereof I hereunto affix my signature in the presence of two witnesses.
